UNITED STATES PATENT OFFICE

NORMAN H. SAUNDERS, OF HOMEWOOD, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed July 14, 1930. Serial No. 467,661.

The present invention relates in general to automatic telephone systems, but more particularly to such systems in which line finders are employed to connect an idle selecting switch with a calling line; and the principal object of the invention, briefly stated, is the production of new and improved circuit refinements in finder switch systems, the improvement tending to make the system more reliable, to give uniform high quality service, and to make it cheaper to install and maintain.

According to another object of the invention the possibility of a finder stopping on a busy line has been further guarded against by providing an improved switching through circuit which permits the finder to pass over test contacts having booster battery potential connected thereto. This improved switching through circuit also permits the use of a less expensive line circuit than has heretofore been used successfully in a system of this type.

As a further object of the invention an improved control equipment, comprising relays, is provided common to a group of finders for controlling the various functions of the finders in that group.

One of the features of the invention relates to the means whereby the finders in a group are successively taken into use by the common control relays and rendered unselectable on release for a succeeding call, although idle, until all the finders, which are selectable in the group, have been taken into use.

Various objects and features not specifically mentioned here will best be understood from reading the detailed description and claims which follow.

The drawings comprising Figs. 1 to 5, inclusive, when arranged with Figs. 1, 2 and 3 from left to right in a straight line or with Figs. 4 and 5 substituted for Figs. 1 and 3 with correspondingly numbered lines in alignment, show sufficient details to enable a clear understanding of this invention.

Referring now to Fig. 1 in more detail, the selector SA shown on the left-hand side is of the old and well known type of Strowger selector and is included in a selector-finder

link. The finder switch FA is of the Strowger vertical and rotary type, having wipers 230 to 235, inclusive, which are moved first in a vertical direction and then in a rotary direction to select the contact of a calling line. The wipers of the finder are shown on the left-hand side of Fig. 2. Since in the present embodiment of this invention a finder switch of 200 line capacity is being used, the finder FA is provided with two sets of wipers, the wipers 230 to 232, inclusive, forming one set of wipers and the wipers 233 to 235, inclusive, the second set. The finder switch FA is also equipped with a vertical test wiper 262, shown in the lower left-hand corner of Fig. 2. The finder comprises only the operating magnets and two switching relays. The two switching relays are relays of the type disclosed in Patent 1,673,884, issued June 19, 1928 to H. C. Pye. The core of these switching relays are provided with two windings which are separated by a magnetic spacing member, a projection of which extends back and forms a back stop against which the armature of the relay rests. The winding on the heel end of the relay is the magnetizing coil, and the flux produced thereby traversing the path including this magnetic iron back stop, which is in shunt of the air gap, and no amount of flux strength in this magnetizing coil will cause the armature to operate. A very small current in the second operating winding of the relay, when in the same direction as the magnetizing winding, will cause the relay to operate. The use of these relays as switching relays permits the calling line to be marked in the finder blanks with a potential through relatively high resistance and impedance and prevents undesired disturbances in the searching circuit upon the test wiper of the finder encountering booster battery potential on a test contact before reaching the test contact of a calling line. All the relays of this type have been shown in the drawings with lugs extending from their center portions.

In the lower half of Fig. 1, there is shown the finder allotter DA comprising the stepping magnet 164, wipers 146 to 151, inclusive, and a plurality of relays for controlling the

various functions of the finders. The allotter DA is common to a plurality of finder-selector links, such as the finder-selector link FA and SA shown in the upper portion of Fig. 1. The allotter DA is mechanically similar to the well known rotary lineswitch while the circuit thereof has been altered in accordance with the present invention.

In Fig. 2 is shown the subscribers' lines S and S', it being assumed for the purpose of illustration that the subscriber S line number is 125, and that the subscriber S' line number is 295. Associated with each line are the usual line and cut-off relays, the circuits of which have been modified in accordance with one of the objects of the present invention. The normal connections from connector banks are shown extending to the line and cut-off relays associated with the subscribers' lines S and S'. In the lower part of Fig. 2 is shown the vertical banks VA and VB, which together with the wipers 262 and 263 determine the vertical designations to which the finder switches are to be operated.

In Fig. 3, there is shown the finder switch FB and selector SB, both switches being duplicates of those shown in Fig. 1 while in the lower half of Fig. 3 the allotter DB is used for allotting calls to finder-selector links in this group. The allotter DB is mechanically the same as the allotter shown in Fig. 1 but the circuits have been modified somewhat in accordance with the present invention. The allotter DB may be substituted for the allotter DA and vice versa without any circuit changes.

In Fig. 4, there is shown a modification of the finder-selector link and the allotter which may be substituted for the finder-selector link and allotter shown in Fig. 1. The selector SAM is identical to the selector SA shown in Fig. 1, while the finder FAM has two additional relays, a transfer relay and a connecting relay. In the lower half of Fig. 4 is shown a group of common control relays which are common to the plurality of finder-selector links in this group, or the A group. This common relay equipment or allotter RDA is somewhat similar to the allotter DA shown in Fig. 1, and instead of having wipers for connecting the common control equipment with the finder a connecting relay is provided in each finder for connecting the common control equipment thereto. A transfer relay is also included in the finder for extending the start circuit to the next idle finder-selector link.

The finder-selector links FBM and SBM and the common control relay group RDB are identical to the equipment shown in Fig. 4 and may be substituted for the switches shown in Fig. 3. The common relays or relay allotter RDB is used for controlling the various functions of the finder-selector links

in the B group, one of which is shown in the upper half of Fig. 5.

Throughout the drawings, I have shown a plurality of batteries to avoid unnecessary complications, while in actual installations there would be but one battery, preferably with its positive pole grounded.

In order to enable a clear understanding of the invention it will now be assumed that the subscriber S initiates a call, and it will be further assumed that the finder FA has been preselected by the finder allotter DA in readiness to handle the call. Responsive to the removal of the receiver from the switchhook at substation S, line relay 201 associated with line S is energized to mark the line calling in the finder bank to render it selectable by placing a battery potential thereon through the winding of the cut-off relay 202, and to place ground upon the start conductor 250. The grounding of start conductor 250 connects ground to the second contact in the bank VA and also closes a circuit for the start relay 163 in the finder allotter DA. In case both the selector SA and the finder FA are in normal position, test relay 161 in the finder allotter DA is energized to complete the start circuit for the finder FA whereupon the finder is started in its vertical movement to hunt for the marking ground placed on the vertical bank VA. Since the calling line S has a finder bank designation of 125 and, since the present call is assumed to be handled by the finder group to which that line is first choice, it will be necessary for the finder to take two vertical steps to reach the level containing the calling line. The placing of ground on conductor 250 and the consequent marking of ground potential on the second bank contact of the bank VA, will cause the finder FA to stop on the second level, at which time its wipers will be rotated into that level to pick out the contacts of the line S. When the wipers are rotated into the level, tests will be made simultaneously by both sets of wipers, the lower set of wipers comprising wipers 233 to 235, inclusive, will test the line upon which they are resting, in this case line 121, and at the same time the upper set of wipers comprising wipers 230 to 232, inclusive, will test the line upon which they are resting, in this case line 221, and if neither one of these lines are calling both sets of wipers will be stepped on to the next contact where the test will be repeated. When the line S is encountered, the battery potential applied to the test contact associated with that line will render it selectable, thereby causing the finder FA to stop thereon and switch through so that the calling line will be connected through to the selector SA.

When the finder switches through to the calling line the switching relay in the finder operates and connects ground to the com-

mon kick-off lead 136 extending to the allotter, whereupon the allotter stepping magnet 164 is operated to prepare the allotter to preselect another idle finder-selector link.

5 The above general operation just described explains the normal operation of the finder and allotter. It may happen in some instances when a finder-selector link, such as that shown in Fig. 1, has been preselected by an allotter and a call is initiated by a subscriber, such as S, that the selector SA may be in an off-normal condition or the finder-selector link may be faulty. In this case test relay 161 in the allotter is not energized and after a time interval relay 165 energizes to operate the stepping magnet of the allotter to cause the allotter to preselect another finder-selector link.

10 In some instances due to fault, the finder may fail to switch through and free the allotter or the allotter may fail to function properly and in such instances a relay in the allotter, controlled by a vibrating spring, is energized. The energization of this relay brings in an alarm and temporarily renders the allotter DA and the finder-selector link, such as FA and SA, inoperative until the trouble or fault is corrected by the attendant. The calls originating in the A group are now 15 handled by the B group allotter and finder-selector links and in case all of the finders in the B group become busy the allotter DA and the finder-selector links in the A group are automatically restored for use.

20 The allotter DA and the finder-selector links, such as FA and SA in the A group, normally handle all the calls from the subscribers in the A group. In case all of the finder-selector links in the A group become 25 busy the busy common relay 162 in the allotter is deenergized and the allotter DB and the finder-selector links, such as FB and SB, handle the calls for the subscribers in the A group. The operation of allotter DB and 30 the finder-selector links, such as FB and SB, of the B group, are similar to the general operation just described for the A group finder-selector links and allotter.

35 The operation of the finders shown in Figs. 4 and 5 are similar to those shown in Figs. 1 and 3 with the exception that in each of the finders a connecting relay is energized to connect the first idle finder in the chain to the common control relay group. A transfer relay, such as relay 404, transfers the call to the next idle finder in the chain in case the finder FAM is busy at the time a call is initiated. The transfer relay is maintained 40 locked up after the finder releases until the busy common relay 461 deenergizes when all of the finders in the chain have been taken into use. By this arrangement the finders of the group are successively taken into use.

45 Having described the general operation of

the system, a detailed description of its operation will now be given.

Assume now that the line S wishes to call. Responsive to the removal of the receiver a circuit may be traced from ground at spring 206, conductor 254, through the switchhook, receiver, transmitter and calling device of substation S, conductor 255, contact 209, and through the winding of line relay 201, to battery.

50 Line relay 201, upon energizing over the above traced circuit, at armature 207 applies a battery potential to the finder test contact through the winding of cut-off relay 202.

55 The application of this battery to the test contact of line 125 renders the line S selectable to the finder. At armature 205 line relay 201 connects ground to conductor 250 to

60 ground the second vertical bank contact in the bank VA and to complete a circuit extending from conductor 250 by way of resistance 251, conductor 260, armature 179 and its working contact of normally energized

65 busy common relay 162, winding of start relay 163, working contact of armature 178 and said armature, interrupter contact 183 of the stepping magnet 164, and through the winding of magnet 164 to battery. Due to

70 the high resistance of start relay 163 the stepping magnet 164 is not energized over this circuit. Start relay 163, upon energizing, at armature 181 prepares a point in the kick-off

75 circuit for the stepping magnet; at armatures 182 and 184 closes a circuit for energizing relay 161 in case the finder-selector link is

80 in normal position or not faulty; and at armature 185 prepares the circuit for the change-over relay 165.

85 In case the finder selector link is in normal position a circuit may be traced for energizing test relay 161 as follows: from ground by way of spring 184, lower winding of relay 161, working contact of armature 182 and said armature, guard wiper 147, conductor 141,

90 vertical off-normal springs 130 in their normal position, release trunk conductor 135, through the upper polarizing windings of switching relays 104 and 105 to battery. The switching relays 104 and 105 are polarized

95 over this circuit but do not operate their armatures. At armature 196 relay 161 opens a previously closed circuit for changeover relay 165 before the slow-acting changeover relay 165 has had time to fully operate. At

100 armature 194 relay 161 closes a circuit over wiper 14 for energizing the line relay 102 of the selector SA, at armature 195 closes a circuit for energizing the vertical magnet 109

105 of the finder; at armature 197 relay 161 completes a locking circuit for itself; at armature 198 and its working contact closes a circuit for maintaining the start relay 163 energized

110 until the finder switches through so in case this finder switch is the last available idle finder the deenergization of the busy common

relay 162 will not open the circuit of the start relay 163; and at springs 199 starts the weight attached thereto to vibrating. Relay 160 is a slow-to-operate relay and, therefore, during the vibration of springs 199 the relay is not energized until a predetermined time after the springs 199 are maintained closed. At the resting contact of armature 198, relay 161 also opens a point in the kick-off circuit so that the operation of the changeover relay 165 will not operate the stepping magnet 164.

Line relay 102 of the selector SA energizes over the following circuit: ground through resistance 193, springs 194, wiper 146, conductor 140, conductor 134, armature 119 and its resting contact and through the upper winding of line relay 102, to battery. At armature 124 relay 102 closes an obvious circuit for energizing the release relay 101 of the selector SA and the release relay at armature 120 grounds the release trunk conductor 135. At armature 121 release relay 101 opens a further point in the release circuit to the selector release magnet 106 and also opens a further point in the circuit to the busy common relay 162 which was previously opened at the resting contact of armature 124. Busy common relay 162, however, is maintained energized over springs 168 and busy common conductor 138 extending to the other idle selectors in the A group.

The circuit for energizing the vertical magnet 109 of the finder may be traced as follows: from ground by way of springs 195, springs 191, armature 186 and its resting contact, wiper 150, conductor 144, and through the winding of vertical magnet 109 to battery. By the operation of the vertical magnet the wipers of the finder are operated in a vertical direction, the wipers 230 to 235, inclusive, being operated opposite the first level of finder bank contacts and the vertical test wiper 262 being operated into engagement with the first vertical bank contact of the vertical bank VA. Since there is no ground potential on this vertical bank contact no circuit is completed for the changeover relay 165. Stepping relay 166 energizes from grounded springs 111 of the vertical magnet over conductor 139 and at armature 191 interrupts the circuit to the vertical magnet 109, whereupon the magnet releases and in turn at springs 111 opens the circuit of the stepping relay 166. Stepping relay 166, upon deenergizing, at armature 191 again completes the circuit for the vertical magnet, whereupon the vertical magnet raises the wipers another vertical step and at springs 111 again completes the circuit for the stepping relay 166. Since the second vertical bank contact has been grounded by the calling subscriber S, a circuit may be traced for energizing the changeover relay 165 as soon as the vertical magnet 109 releases responsive to the energization of the stepping relay 166. The circuit

for energizing the changeover relay may be traced as follows: from ground by way of springs 205, conductor 250, second vertical bank contact, vertical test wiper 262, conductor 174, conductor 145, wiper 151, armature 189 and its resting contact, springs 185, and through the lower winding of changeover relay 165 and the winding of stepping relay 166 to battery. The stepping relay 166 is held energized in series with the changeover relay 165 until such time as the changeover relay 165 is fully energized and has opened the original energizing circuit for itself at armature 189 after having first completed a locking circuit for itself at armature 188.

Changeover relay 165, upon energizing, at armature 186 transfers the stepping circuit from the vertical magnet 109 to the rotary magnet 108; at springs 187 prepares a circuit for the operating winding of switching relay 108; at armature 189 and its working contact prepares a circuit for the operating winding of switching relay 105; and at armature 190 closes a circuit for maintaining the start relay 163 in energized position independent of the busy common relay 162. Stepping relay 166, upon deenergizing responsive to the operation of the changeover relay 165, at armature 191 closes a circuit for energizing the rotary magnet 108 as follows: from ground by way of armature 195, armature 191, armature 186 and its working contact, wiper 149, conductor 143, armature 154 and its resting contact, armature 158 and its resting contact, and through the winding of rotary magnet 108 to battery. Rotary magnet 108, upon energizing advances the wipers 230 to 235, inclusive, into engagement with the first contact in the second level and also rotates the vertical test wiper 262 out of engagement with the contacts of the vertical bank VA. At interrupter springs 110 rotary magnet 108 completes a circuit for stepping relay 166, whereupon that relay energizes and opens the circuit of the rotary magnet. Further rotation of the wipers of the finder FA are dependent upon whether the test wipers 231 and 234 encounter a negative battery potential or not. In case negative battery potential is not on either of the test contacts with which the test wipers 231 and 234 are now in engagement neither of the switch through or test relays 104 or 105 will energize. Therefore, when the rotary magnet 108 energizes the stepping relay 166 the stepping relay 166 in turn opens the circuit of the rotary magnet 108, the rotary magnet in turn will open the circuit of the stepping relay 166, whereupon the stepping relay deenergizes and again closes a circuit for the rotary magnet 108. This cycle of operation continues until one of the test wipers 231 or 234 encounters a negative battery potential.

Assuming that no other line in the second level of the finder bank terminals are calling, except subscriber S, then when test wipers 231 and 234 are rotated into engagement 5 with the fifth set of contacts the test wiper 234 will encounter a negative battery potential which is applied thereto through the winding of relay 202. When test wiper 234 encounters this battery potential, switching 10 relay 105 energizes over the following circuit: from ground by way of the working contact of armature 189 and said armature, wiper 151, lower winding of switching relay 105, conductor 173, test wiper 234, the test 15 contact engaged thereby, conductor 256, armature 207, and through the winding of cut off relay 202 to battery. Testing relay 105 and cut-off relay 202 energize in series over the above traced circuit. It should possibly 20 have been mentioned that when the release relay 101 of the selector SA grounded the release trunk conductor 135, a circuit was closed through the upper winding of both switching relays 104 and 105 to energize the 25 polarizing windings of such relays. The circuit just traced through the lower winding of switching relay 105 assists the circuit through the polarizing winding with the result that the switching relay 105 energizes 30 very quickly to stop the rotation of the wipers.

It might also be mentioned at this time that in case either of the test wipers 231 or 35 234 should encounter a booster battery metering potential or a busy ground potential during their rotation before the calling line is reached the booster battery potential or the busy ground potential encountered would naturally close a circuit through the lower winding of the switching relays but these 40 circuits would be in opposition to the circuit through the polarizing winding with the result that the switching relay would not be operated.

The cut-off relay 202 at armatures 206 and 45 209 disconnects the line relay 201 and the normal battery and ground connections from the subscriber's line conductors; and at armature 208 completes a locking circuit for 50 itself and also prepares a circuit for guarding the line from intrusion by way of the connector banks. Line relay 201, upon de-energizing, at armature 205 removes ground from the conductor 250.

Returning now to the finder FA and when 55 switching relay 105 energizes in series with the cut-off relay 202, it should be stated that armature 158 operates very quickly and opens the circuit to the rotary magnet so that there 60 is no possibility of the rotary magnet operating to step the wipers an extra step after the calling potential has been encountered by the test wiper 234. At armatures 156 and 159 switching relay 105 connects up the lower 65 set of wipers 233 and 235. At armature 157

relay 105 connects the grounded release trunk conductor 135 to test wiper 234 by way of conductor 173 to ground the test contacts in both the finder and connector banks so that the same will test busy to other finders and to connectors, respectively, having access thereto. The closure of springs 157 temporarily short-circuits the lower winding of relay 105 but this has no effect on a relay of 70 this type because after it is once operated the relay is maintained energized by its polarizing winding until ground is removed from the release trunk connector 135. At the working contact of armature 158 relay 105 connects the ground at armature 195 to the common kick-off conductor 136 for energizing the stepping magnet 164 of the allotter DA. 75

When the switching relay 105 connects the line conductors of the calling line S to conductors 134 and 137 dial tone is connected 80 over these conductors to the calling line in the well known manner and when the calling subscriber S hears the dial tone the subscriber will know that the finder has found and connected with his line, and that he may proceed 85 to set up the desired connection to the called party. Since the operation of the selector SA and the remaining switches in the switch train to the called line is old and well known it is, therefore, not necessary to describe 90 or show their operation. By means of the vertical off-normal springs 129 on the finder and also the switching relay 103 of the selector one of the grounded multiple circuits of the common busy relay 162 is opened. In 100 case all of the selectors in the A group or all of the finders in the A group are busy or in an off-normal condition all of the multiple grounds to conductor 138 would be removed and the circuit for the busy common relay 105 105 162 would be opened.

Returning now to the allotter DA and at a time when the stepping magnet 164 was energized responsive to the operation of switching relay 105, the magnet 164 upon energizing, at its interrupter springs 183 opens the circuit of the start relay 163. Start relay 163 thereupon deenergizes and at armatures 182 and 184 opens the locking circuit of relay 161 whereupon the latter relay releases, and at armature 181 opens the circuit to the stepping magnet 164. At armature 194 relay 161 115 disconnects ground from conductor 134 so that the impulses transmitted by the calling subscriber's calling device may be effective for 120 operating the line relay of the selector; at armature 195 disconnects ground from the stepping and kick-off circuit; at armature 197 opens another point in its own locking circuit; at armature 198 opens a point in the 125 circuit for the start relay 163; and at vibrating springs 199 opens the energizing circuit of relay 160 before the slow-acting relay 160 has had time to fully operate. At armature 195 relay 161 also opens the locking circuit of 130

120 subscriber's calling device may be effective for operating the line relay of the selector; at armature 195 disconnects ground from the stepping and kick-off circuit; at armature 197 opens another point in its own locking circuit; at armature 198 opens a point in the 125 circuit for the start relay 163; and at vibrating springs 199 opens the energizing circuit of relay 160 before the slow-acting relay 160 has had time to fully operate. At armature 195 relay 161 also opens the locking circuit of 130

changeover relay 165 whereupon the latter relay is deenergized. Relay 165, upon deenergizing at armatures 187 and 189 disconnects ground from the lower operating windings of the switching relays 104 and 105 and at armatures 190 opens another point in the circuit for maintaining the start relay 163 in operated position. The switching relay 105 is maintained in operated position by its upper polarizing winding.

Stepping magnet 164, upon deenergizing, advances its wipers 146 to 151, inclusive, into engagement with the next set of bank contacts leading to the succeeding finder-selector link in the A group. In case such finder-selector link is in an off-normal position and is busy the vertical off-normal springs corresponding to vertical off-normal springs 130 are operated to connect ground to guard conductor, such as guard conductor 141, which in this case will extend to the succeeding bank contact with which the wiper 147 is now in engagement. This ground connection will extend by way of wiper 147, armature 182 and its resting contact, armature 178, interrupter springs 183 of the stepping magnet 164, and through the winding of the stepping magnet 164, to battery. Magnet 164 operates in a buzzer-like manner as long as wiper 147 encounters busy ground potential and as soon as wiper 147 encounters a guard conductor leading to an idle finder-selector link the wipers of the allotter come to rest in such position to preselect this idle finder-selector link for the next calling party. The finder allotter DA, therefore, preselects another idle finder-selector link as soon as the finder with which it is associated has switched through and established connection with the calling line.

Since the finder FA is a 200-point finder and, therefore, has two sets of wipers it may so happen that test wiper 231 instead of test wiper 234 may encounter the negative battery calling potential of the calling line, while the test wiper 234 does not. In this case the finder is operated in the same manner as previously described and when wiper 231 encounters the negative battery calling potential on the test contact, associated with the calling line, a circuit will be completed for operating the switching relay 104 as follows: from ground by way of armature 187, wiper 147, conductor 142, through the lower operating winding of switching relay 104, conductor 172, test wiper 231 and associated test contact to negative battery potential. Switching relay 104, upon energizing, at armatures 152 and 155 connects the upper set of wipers for use. At armature 153 relay 104 connects the grounded release trunk conductor to the test contact of the calling line for guarding purposes and at armature 154 opens the circuit to the rotary magnet, and also completes the circuit to the kick-off con-

ductor for kicking the allotter off to pre-select another idle selector-finder link.

In case the test wipers 231 and 234 should simultaneously encounter calling potentials both switching relays 104 and 105 will energize and the energization of the switching relay 105 will be ineffective because the switching relay 104 disconnects the lower set of wipers. The calling subscriber may now complete the connection to the desired called subscriber in the well known manner.

When the called subscriber answers, the slow-releasing meter relay in the connector is momentarily energized to momentarily connect booster battery over the release trunk to operate the meter of the calling subscriber. A metering arrangement of this type is shown and described in Patent No. 1,186,823, issued June 13, 1916 to F. Newforth, Jr.

After the conversation and responsive to the calling subscriber replacing the receiver, ground is removed from the holding conductor of the connector switch in the well known manner, whereupon the circuit of the switching relay 103 of the selector SA is opened. Switching relay 103, upon deenergizing, completes the release circuit for the release magnet 106 of the selector in the well known manner, whereupon the selector returns to its normal position. The release of switching relay 103 also closes the release circuit for the release magnet 107 of the finder FA by way of armature 126, armature 124, and test set springs 127 to the finder vertical off-normal springs 129. Release magnet 107 of the finder energizes and restores the finder FA to its normal position. When ground was removed from the holding conductor in the connector switch, ground was also removed from release trunk conductor 135 whereby the circuit extending through the polarizing windings of switching relays 104 and 105 was opened to cause the deenergization of such relays. When the selector SA and finder FA reach their normal positions the circuit for their respective release magnets are opened at the off-normal springs and the switches are ready to be used in another call.

Referring again to allotter DA shown in Fig. 1, and at a time when the start relay 163 has been energized responsive to a call, it will now be assumed that negative battery is not connected to guard conductor 141 because the selector SA or finder FA is in an off-normal position or because of some fault. Under these conditions the circuit for relay 161 will not be completed and, therefore, the slow-to-energize changeover relay 165 will have had time to fully operate. The circuit for energizing changeover relay 165 extends by way of ground at armature 184, armature 196, and through the winding of changeover relay 165 to battery. At armature 190 relay 165 energizes and completes the circuit for energizing

the stepping magnet 164 which in turn at interrupter spring 183 interrupts the circuit of the start relay 163 so that the start relay 163 will deenergize and open the circuit for the stepping magnet 164 and the changeover relay 165. The deenergization of the stepping magnet 164 steps the wipers of the allotter DA to another idle finder-selector link, and when such idle link is found the call will be proceeded with in the same manner as previously described.

Another condition which may arise is that the finder may not switch through within a predetermined time due to some fault. Consider now the case in which the finder has been seized and operated but has failed to switch through within a predetermined time and, therefore, the allotter has not kicked-off and has not opened the circuit to the slow-to-operate relay 160. Under these conditions the vibrating spring 199 after a predetermined time stops vibrating and is maintained in contact, whereupon the slow-to-operate relay 160 is operated. Relay 160 at armature 192 completes a locking circuit for itself from ground by way of conductor 114, jack springs 169, armature 192, and through the winding of relay 160 to battery. When this occurs relays 161, 162, 163 and 165 are in energized position. At armature 168 relay 160 opens a point in the circuit of the busy common relay 162 and at armature 167 completes a circuit for operating the stepping magnet 164 as follows: ground by way of armature 195, armature 167, armature 181, and through the winding of stepping magnet 164 to battery. Stepping magnet 164, upon energizing, at springs 183 interrupts the circuit of the start relay 163 whereupon the start relay deenergizes. At armature 181 relay 163 opens the circuit of the stepping magnet 164 to cause the wipers of the allotter to advance to the next finder-selector link, and at armature 182 and its resting contact prepares the pre-selecting circuit of the allotter; at armatures 182 and 183 opens the locking circuit of relay 163 which deenergizes. Relay 161, upon deenergizing, at armature 195 opens the locking circuit of relay 165, whereupon the latter relay deenergizes; and at the vibratory springs 199 opens the original energizing circuit of slow-to-operate relay 160 which relay, however, is maintained over the previously traced locking circuit. All of the relays in the allotter DA except relay 160 are deenergized and the relay 160 is maintained energized to maintain the circuit to the busy common relay 162 open so that any calls originating from the A group will now be transferred to the allotter DB and calls will be handled by the finder-selector links, such as FB and SB shown in Fig. 3. This transfer circuit is accomplished at armature 179 and its resting contact. At armature 178 busy common relay opens the stepping circuit of the stepping

magnet 164 to prevent the operation of the magnet 164, and at armature 180 removes ground from conductor 115 to open a locking circuit for the supervisory lock-out in the allotter DB in case this relay should be energized at this time. Before the attendant in the switch room corrects the fault, the calls originating in the A and B group are handled by the allotter DB and the finder selector-links of the B group. In case all of the finder-selector links in the B group should become busy the busy common relay in the allotter DB deenergizes and disconnects ground from conductor 114 whereupon the locking circuit of relay 160 is opened and the relay deenergizes to again complete the circuit for the busy common relay 162. After relay 162 energizes the calls are handled by the allotter and finder-selector links in the A group in the same manner as previously described.

Assume now that at the time the substation is connected with a call all of the finders in the group containing the finder FA are busy, in which case the call will be handled by the finder in the group containing the finder FB, provided no call is in progress at this time in the B group. It will be noted that the placing of ground on conductor 250 and contact 2 of the vertical bank VA also places ground upon contact 9 of the vertical bank VB. It will be noted that the banks of the finder are slipped between group A and group B so that the banks appearing in the lower half of group A appear in the upper half of the banks of group B. Responsive to the grounding of conductor 250, and in case all of the finder selector links, such as FA and SA, are busy the busy common relay 162 will be deenergized position and, therefore, the start relay in the allotter DB is energized to start a finder in the B group, for example finder FB, in operation in a vertical direction until the vertical wiper 263 encounters the marked bank contact, in this case the ninth bank contact in the vertical bank VB. The wipers of the finder are stopped at this level and rotated in a horizontal direction into engagement with the bank contact of the calling line.

In a similar manner calls from the line S' have as its first choice the finders in the B group and are handled by the B group switches in a manner somewhat similar to the manner described for the A group switches. While the finder selector links in the A and B groups are identical it will be noted that the circuits of the allotters DA and DB are different and in order to describe the operation of the allotter DB it will be assumed that the line S' initiates a call.

Responsive to subscriber S' removing his receiver line relay 203 is energized over conductors 257 and 259 and the called subscriber's loop. At armature 210 line relay 203 grounds the second bank contact 2 in the vertical bank VB and also connects ground to

start conductor 261 by way of resistance 253. At armature 212 relay 203 connects negative battery through the winding of cut-off relay 204 to the test contact of the calling line to mark the line S' calling.

- 6 Responsive to the grounding of conductor 261 start relay 359 is energized by way of armature 381 and this relay at armature 384 completes a circuit for operating the differential relay 357 as follows: from ground by 10 way of armature 374, armature 380, armature 384, armature 387 and its resting contact, and through the lower winding of differential relay 357 to battery. At armature 385 start relay 359 prepares a circuit for two-step relay 355 and at armature 386 closes a circuit for energizing auxiliary start relay 362 in case the relay 362 is not short-circuited over the guard wiper 347. Differential relay 15 357 energizes and starts the weighted springs 377 and 378 vibrating. In case the allotter DB and the finder-selector links function properly the differential relay 357 at this time performs no useful function.
- 20 In case the auxiliary start relay 362 is not short-circuited by way of guard wiper 347, relay 362 energizes over the following circuit: ground by way of armature 382 armature 386, winding of relay 362, armature 379, 25 interrupter springs 376, and through the winding of the stepping magnet of the allotter 363 to battery. Due to the high resistance of the auxiliary start relay 362 the stepping magnet 363 is not energized over the above traced circuit. Relay 362, however, 30 energizes and at armature 394 closes a circuit for energizing the line relay 302 of the selector SB; at armature 395 closes a circuit for energizing the vertical magnet 309; at armature 396 prepares a locking circuit for 35 changeover relay 360; at armature 397 opens the circuit extending through the lower winding of differential relay 357 at its resting contact and at its working contact closes a circuit for energizing the upper winding of 40 the differential relay 357. At armature 398 relay 362 prepares a circuit for the changeover relay 360 and at armature 399 closes a locking circuit extending from 45 grounded armature 369 to the winding of the busy common relay 359 for temporarily maintaining the busy common relay locked in its energized position. Line relay 302 in the selector SB energizes over the following 50 circuit: from ground by way of armature 394, wiper 346, conductor 340, conductor 384, armature 319 and its resting contact and through the upper winding of line relay 302, to battery. At armature 324 line relay 302 55 energizes the selector release relay 301 and the latter relay, upon energizing, at armature 320 grounds release trunk 335 and also energizes the upper polarizing windings of switching relays 304 and 305 of the finder 60 SB. At armature 326 line relay 302 also dis-

connects one of the multiple ground connections connected to busy common conductor 338 for maintaining the busy common relay 358 in the allotter energized. When the circuit extending through the lower winding 70 of differential relay 357 is opened by the operation of armature 397 and a circuit is closed through the upper winding of differential relay 357 by way of grounded armature 374, armature 380, armature 384, armature 397 75 and its working contact, armature 390 and its resting contact, armature 393 and its resting contact, and through the upper winding to battery, magnetic flux is built up in opposition to the magnetic flux created by the lower winding with the result that the differential relay 357 releases its armatures 377 and 378 and very shortly thereafter reoperates these armatures to start the weighted springs 377 or 378 have stopped vibrating to maintain its circuit closed for a certain interval.

90 The circuit for energizing the vertical magnet 309 may be traced as follows: from ground by way of armature 394, normally closed springs controlled by armature 392 of the interrupter relay 361, armature 388 95 and its resting contact, wiper 350, conductor 344, and through the winding of vertical magnet 309 to battery. By the operation of the vertical magnet 309 the wipers 236 to 241, inclusive, and the vertical test wiper 100 263 are operated vertically one step to position the vertical wiper 263 in engagement with the first vertical contact 1 in the vertical bank VB, and to position the wipers 236 to 241, inclusive, opposite the first level of 105 line bank contacts. The vertical off-normal springs 329 are operated responsive to this first vertical step to prepare a circuit for the release magnet 307 of the finder and to open one of the multiple ground connections connected to busy common conductor 338. At vertical off-normal springs 330 ground is connected to conductor 341 for preparing a further point in the locking circuit of the 110 changeover relay 360. At armature 311 vertical magnet 309 completes an energizing circuit for the stepping or pulse ending relay 361 as follows: from ground by way of armature 311, conductor 339, and through the winding of relay 361 to battery. At armature 115 393 relay 361 opens the circuit extending through the upper winding of differential relay 357 at its resting contact and at its working contact closes a circuit for energizing the lower windings of differential relay 120 357. This results in the differential relay being deenergized and immediately reenergized to cause the weighted springs 377 and 378 to start vibrating over again. At armature 392 stepping relay 361 opens the circuit of the 125 357.

vertical magnet 309 and the vertical magnet upon releasing at armature 311 opens the circuit of the stepping relay 361. This interaction between the vertical magnet 309 and the interrupter relay 361 continues until the vertical test wiper 263 encounters a ground potential upon the test contact of the vertical bank VB. In this case since the #2 vertical test contact is grounded the finder will have taken two steps to reach this contact and as a result thereof a circuit may be traced for energizing cut-off relay 360 when ground is removed from conductor 339. This circuit may be traced as follows: from 5 grounded test contact 2, wiper 263, conductor 374, conductor 345, wiper 351, armature 391 and its resting contact, armature 398, lower winding of cut-off relay 360, and through the winding of stepping relay 361 to battery. In this circuit the relay 361 is maintained energized in series with the cut-off relay 360 until the cut-off relay has completed its locking circuit at armature 389 and has thereafter opened its original energizing circuit at armature 391. At armature 390 changeover relay 360 completes a circuit for energizing the upper winding of the differential relay 357 with the result that the differential relays 357 again gives the weighted springs an additional kick to keep the springs vibrating. At armature 387 changeover relay 360 prepares a circuit for the operating winding of polarized relay 304 and at armature 391 and its working contact prepares a circuit for the operating winding of switching relay 305 and at its resting contact opens its original energizing circuit and the circuit of the stepping relay 361. At armature 388 changeover relay 350 changes the stepping circuit from the vertical magnet to the rotary magnet. The locking circuit for changeover relay 360 extends by way of finder vertical off-normal springs 330, conductor 341, wiper 347, armature 396 and its working contact, armature 389 and through the upper winding of changeover relay 360 to battery. As soon as the stepping relay 361 deenergizes, the stepping circuit for the rotary magnet 308 is completed by way of ground from armature 395, through the normally closed springs controlled by armature 392, armature 388 and its working contact, wiper 349, conductor 343, armature 354 and its resting contact, armature 358 and its resting contact, and through the winding of rotary magnet 308 to battery. By the operation of the rotary magnet the wipers of the finder are rotated onto the first rotary contact in this level, and at armature 310 the circuit for again energizing the stepping relay 361 is completed. The stepping relay 361 at armature 392 again opens the circuit to the rotary magnet. Further rotation of the wipers are now dependent upon the test 10 wipers encountering a calling potential. By the operation of relay 361 the stepping circuit to the rotary magnet is interrupted and the rotary magnet interrupts the circuit of the stepping relay 361 with the result that this interaction between the rotary magnet 308 and stepping relay 361 steps the wipers of the finder step-by-step over the rotary contacts until a calling potential is encountered by one of the test wipers 237 or 240. When test wiper 237 encounters the calling potential applied to the test contact of line S' a circuit may be traced for operating switching relay 304 as follows: from ground by way of armature 387, wiper 348, conductor 342, lower operating winding of switching relay 304, conductor 372, wiper 237, test contact of line S', conductor 258, armature 212, and through the winding of cut-off relay 204 to battery. Cut-off relay 204 and switching relay 304 energize in series, the cut-off relay 204 to disconnect the line relay 203, battery and ground connection from the subscriber's line and the switching relay 304 to connect the upper set of wipers to the talking conductors 334 and 337 at armatures 352 and 355. At armature 353 switching relay 304 connects the grounded release trunk conductor 335 to the test contact of line S' to guard the line against intrusion and at armature 354 and its resting contact opens the circuit extending to the rotary magnet 308 and at its working contact connects the stepping circuit to common kick-off conductor 336. The calling subscriber S' may now complete the remainder of the connection in the well known manner. 15

Returning now to allotter DB and at the time that the common kick-off conductor 336 was grounded, a circuit may be traced for operating the stepping magnet 363 of the allotter as follows: ground by way of armature 395, normally closed springs controlled by armature 392, armature 388 and its working contact, armature 354 and its working contact, conductor 336, and through the winding of magnet 363, to battery. At interrupter springs 376 magnet 363 opens the circuit of the auxiliary start relay 362 whereupon the latter relay deenergizes. Relay 362, upon deenergizing, at armature 394 removes ground from the upper winding of line relay 302 so that the line relay may be effective responsive to the impulses; at armature 395 disconnects ground from the stepping and kick-off circuits at armature 396 opens the locking circuit of changeover relay 360 at its working contact and at its resting contact prepares the stepping circuit for the allotter DB at armature 397 again reverses the circuit to the differential relay 357 in case the start relay 359 is maintained energized; and at armature 399 opens the locking circuit extending through the winding of busy common relay 358, so that the latter relay may release in case all of the finder-selector 20 25 30 35 40 45 50 55 60 65 70 75 80 85 90 95 100 105 110 115 120 125 130

links are busy. Since the stepping circuit through magnet 363 is now opened at armature 395, the magnet deenergizes and steps the wipers 347 to 351 to the contacts of the 5 next finder-selector link and in case this finder-selector link is busy, wiper 347 will encounter a ground potential with the result that the stepping magnet is again energized and again interrupts its own circuit to step 10 the wipers step-by-step in search of an idle finder-selector link. Magnet 363 continues to operate in a buzzer-like manner stepping the wipers until wiper 347 no longer encounters a ground or busy potential whereupon 15 the wipers stop in engagement with the next idle finder-selector link.

When the line relay 203 deenergizes, responsive to the energization of cut-off relay 204, line relay 203 at armature 210 removes 20 ground from start conductor 362 to deenergize the start relay 359. However, in case another subscriber in the B group were calling at this time the start relay 359 would be maintained energized and the auxiliary start 25 relay 362 would be maintained short-circuited from the ground potential encountered by wiper 347 until the allotter had preselected the next idle finder-selector link.

The above described operation is the normal 30 operation of the allotter DB and therefore the differential relay 356 controlled by vibrating springs 377 and 378 has not energized because the differential relay 357 has not been maintained closed by the vibrating 35 springs 377 and 378. It will now be assumed, however, that through some fault the auxiliary start relay 362 has not functioned properly after the line relay 359 has energized responsive to a call. In this case the previously 40 traced circuit for the differential relay 357 is maintained closed for a sufficient time interval to permit the vibrating springs 377 and 378 to be maintained in engagement and a circuit may, therefore, be traced for operating 45 differential relay 356 as follows: from ground by way of armature 374, armature 380, armature 384, armature 397 and its resting contact, vibrating springs 378 now closed, and through the lower winding of differential relay 356 to 50 battery. At armature 373 differential relay 356 completes a circuit for energizing the stepping magnet 363; at armature 374 opens its own energizing circuit as well as the circuit extending to the lower winding of differential relay 357; and at armature 375 completes a circuit for energizing two-step relay 355 in its first step to close only springs 372. This latter circuit may be traced from grounded armature 385, armature 375, armature 371 and 55 its resting contact, and through the upper winding of two step relay 355 to battery. Two step relay 355 operates only armature 372. After an interval of time, differential relay 356 deenergizes and at armature 373 opens the 60 circuit to stepping magnet 363, whereupon the

wipers of the wipers of the allotter DB are advanced one step; at armature 374 again prepares a circuit for the differential relay 357; and at armature 375 removes the short-circuit from around the lower winding of two-step relay 355 with the result that relay 355 is operated by means of its two windings in series through its second step to operate armatures 370 and 371. At armature 370 two-step relay 355 closes a circuit for energizing the slow-to-operate alarm relay 353 and at armature 371 prepares a circuit for energizing the emergency alarm relay 354. At armature 355 relay 353 closes a circuit for operating an alarm which indicates to the attendant a minor case of trouble, and at armature 366 completes a locking circuit for itself from grounded conductor 115 by way of jack springs 364. Now in case the auxiliary start relay 362 operates properly when the next finder-selector link 65 has been preselected the differential relay 357 is operated in a manner previously described and the differential relay 356 does not operate a second time and the switches operate in the same manner as previously described. However, in case relay 362 does not operate when the new selector-finder link is selected, then differential relay 356 is energized after a time to operate a second time, this time closing the circuit to relay 354 which energizes and locks up at armature 368 and at armature 369 sends in an emergency alarm. At armature 367 relay 354 opens the circuit of busy common relay 358 and the latter relay deenergizes and transfers the calls to the A group in the same manner as described for the transfer calls from the A group to the B group. In the same manner as just described and in case stepping relay 361 or the changeover relay 360 do not function properly within a predetermined time the differential relay 357 is maintained energized for a sufficient time to energize differential relay 356 to cause the allotter to send in an alarm, to step the allotter off this particular finder-selector link, and to bring in an emergency alarm in case the same fault occurs after the allotter has selected another finder-selector link. The reasons for the two alarms is that if only the ordinary alarm is sounded then the trouble is of a minor nature, possibly in the finder-selector link, and if the attendant is busy on other important work the trouble can be ignored for the present but when an emergency alarm is sounded then the trouble is fairly serious and in all probability the trouble is in the allotter and, therefore, the whole B group is unavailable for handling calls. The attendant, therefore, when he hears the emergency alarm will immediately take whatever steps are necessary to correct the fault.

In order to describe the modifications shown in Figs. 4 and 5, Fig. 4 will be substituted for Fig. 1 and Fig. 5 will be substituted for Fig. 3. Responsive now to the re-

removal of the receiver by calling subscriber S conductor 260 is grounded responsive to the operation of the line relay 201 and the start relay 464 is energized over the following circuit: from grounded conductor 260, armature 471 and its working contact, armature 474, armature 487, and through the winding of start relay 464 to battery. At armature 481 relay 464 connects negative battery thru resistance 480, to conductor 451 and thence by way of normally closed springs controlled by armature 429 through the winding of connecting relay 405 to ground. At armature 459 relay 464 prepares a locking circuit for relays 463 and 465 and also prepares the stepping circuit for the vertical and rotary magnets of the finder; and at armature 482 closes a circuit for energizing the slow-to-energize changeover relay 465 which circuit, however, is opened at armature 475 before the slow-acting relay 465 has had time to fully operate. Connecting relay 405, upon energizing over the above traced circuit, at armature 430 closes a circuit for energizing testing relay 463 and for energizing the polarizing windings of relays 406 and 407; at armature 431 and its resting contact opens a point in one of the locking circuits of transfer relay 404; at armatures 432 and 433 prepares the circuits through the operating windings of the switching relay 406 and 407; armature 434 prepares the circuit for the rotary magnet 409; and at armature 435 completes an energizing circuit for the vertical magnet 410. The circuit for energizing the test relay 463 may be traced as follows: from ground by way of armature 477, lower winding of relay 463, conductor 454, armature 430, release trunk conductor 415, and through the polarizing windings of switching relays 406 and 406 to battery. At armature 476 relay 463 completes a locking circuit for itself before it opens its own original energizing circuit at armature 477. At armature 475 relay 463 opens the circuit for slow-acting changeover relay 465 before the same has had time to fully operate; at armature 478 starts the springs 478 vibrating; and at armature 479 closes a shunt around armature 487 to maintain the start relay energized independent of changeover relay 465. The circuit for energizing vertical magnet 410 may be traced as follows: from ground by way of armature 459, normally closed springs controlled by armature 488, armature 483 and its resting contact, common vertical conductor 456, armature 435, and through the winding of vertical magnet 410 to battery. By the operation of vertical magnet 410 the finder wipers 230 to 235, inclusive, and the vertical wiper 262 are operated one vertical step and the off-normal springs 412 and 413 operate to prepare circuits for the finder release magnet 457 and to connect ground to armature 427 of the transfer relay 404 to prepare a lock-

ing circuit for the same. At armature 447 vertical magnet connects ground to common conductor 455 for energizing the stepping relay 466. The inter-action between the vertical magnet 410 and stepping relay 466 is the same as described for Fig. 1 and when the vertical wiper 262 encounters the ground potential on the second contact of the vertical bank VA a circuit may be traced for energizing the changeover relay 465 as follows: from grounded vertical test contact 2 of vertical bank VA, wiper 262, conductor 174, armature 433, common conductor 452, armature 486 and its resting contact, through the lower winding of changeover relay 465, and through the winding of stepping relay 466 to battery. This circuit is effective to energize the changeover relay when the vertical magnet has deenergized and removed ground from the common conductor 455. Stepping relay 466 is maintained energized in series with the changeover relay 465 until relay 465 opens its own original energizing circuit at armature 486 after it has closed a locking circuit for itself through armature 485 and its upper winding. At armature 483, relay 465 disconnects the stepping circuit from the common vertical stepping conductor 456 at its resting contact and at its working contact connects the stepping circuit to the common rotary stepping conductor 453 to prepare a circuit for the rotary magnet 409. At armature 484, relay 465 prepares a locking circuit for the kick-off relay 462 and at armature 486 and its working contact prepares a circuit for the lower operating winding of switching relay 407; and at armature 487 opens the original energizing circuit of start relay 464 which circuit, however, is maintained at armature 479. Since the armature 486 opens the holding circuit of stepping relay 466, the latter relay releases and closes the circuit for energizing rotary magnet 409 as follows: from ground by way of armature 459, normally closed springs controlled by armature 488, armature 483 and its working contact, common rotary conductor 453, armature 434, armature 439 and its resting contact, armature 444 and its resting contact, and through the winding of rotary magnet 409 to battery. At armature 446 rotary magnet 409 grounds the common conductor 455 to cause the energization of the stepping relay 466 which in turn opens the circuit to the rotary magnet 409. This inter-action between the rotary magnet 409 and stepping relay 466 continues until one of the test wipers 231 or 234 encounters a calling potential or a negative battery potential connected to the test contact. When test wiper 234 encounters the negative battery potential applied to the test contact of line S by way of cut-off relay 202 testing relay 407 is operated by way of conductor 173, its lower winding, armature 433, common conductor 452 and ar-

mature 486 and its working contact to ground. Since both the switching relays 406 and 407 had their upper windings or polarizing windings energized by way of armature 430 when relay 405 energized the switching relay 407 immediately operates and at armatures 441 and 445 connects the calling subscriber's loop through to the line relay 402 of the selector SAM. At armature 442 relay 407 disconnects one of the multiple ground connections from busy common conductor 448; at armature 443 prepares a circuit for connecting release trunk ground to conductor 173 to guard the line against intrusion, it being remembered that after the switching relays have once been operated the circuit through their polarizing windings will maintain such relays in energized position; and at armature 444 connects ground by way of common kick-off conductor 450 to kick-off relay 462. At armature 444 and its resting contact, switch relay 407 opens the circuit of the rotary magnet 409 before the stepping circuit is again completed, so as to prevent the wipers from taking an additional rotary step. When the stepping relay 466 deenergizes a circuit may be closed for energizing kick-off relay 462 as follows: grounded armature 459, normally closed springs controlled by armature 488, armature 483 and its working contact, conductor 453, armature 434, armature 439 and its resting contact, armature 444 and its working contact, common kick-off conductor 450 and through the winding of kick-off relay 462 to battery. Relay 462 at armature 473 completes an obvious locking circuit for itself from grounded armature 484 and at armature 474 opens the circuit to the start relay 464, whereupon the latter relay releases. At armature 481 start relay 464 opens the shunt circuit around the upper winding of the transfer relay 404, thereby permitting the transfer relay to energize in series with the connecting relay 405; and at armature 459 opens the original energizing circuit of the kick-off relay 462 and opens the locking circuit of relays 463 and 465. Relay 463 deenergizes before the slow-to-operate relay 460 has had time to fully operate and relay 465 after an interval of time for which it is adjusted deenergizes and opens the locking circuit of kick-off relay 462 at armature 484.

When the switching relay 407 connects the calling subscriber's loop in series with the line relay 402 of the selector the line relay energizes and at armature 423 completes a circuit for the release relay 401 whereupon the latter relay prepares the selector for operation and at armature 419 grounds the release trunk conductor 415 for maintaining the switching relays energized after the release of relay 405 as well as for guarding the calling line against intrusion.

When transfer relay 404 energizes in series with relay 405 as a result of the deenergiza-

tion of the start relay 464, transfer relay 404 at the normally closed springs controlled by armature 429 opens the circuit of connecting relay 405 whereupon the latter relay deenergizes. At armature 429 and its working contact, transfer relay 404 connects the start in conductor 451 to the start out conductor 414 extending to the next finder in the chain and at armatures 427 and 428 completes two locking circuits for itself. The upper locking circuit extending from grounded off-normal springs by way of armature 427 and its upper winding maintains the transfer relay in energized position as long as the finder is in an off-normal position. The other locking circuit extends by way of armature 470, holding conductor 449, armature 428 and through the lower winding of transfer relay 404 to battery. This holding circuit is effective until each of the finders in the group have been taken into use and when the last finder in the chain, or A group, has been taken into use all of the multiple grounds are disconnected from the busy common conductor 448 at armatures, such as armature 426, and the busy common relay 461 will thereupon release and open all of the locking circuits extending to all of the transfer relays, such as 404, which at that time are locked up. This arrangement causes each finder in the chain to be taken into use in proper sequence, providing of course, such finders have been released before all of the finders in the chain have been used on preceding calls. At armature 426, transfer relay 404 prepares a point in the circuit of the finder release magnet 457. Connecting relay 405, upon deenergizing, at armatures 430, 433, 343 and 435 disconnects the common control relay group RDA from the finder switch. It can be seen, therefore, that on subsequent calls when the start relay 464 is energized that the start circuit will be completed for the connecting relay of the succeeding finder by way of conductor 414.

The calling subscriber may now complete the connection to the called subscriber in the well known manner and metering will take place as illustrated in Fig. 1. After conversation in response to the subscribers replacing their receivers ground is removed from the release trunk of the connector switch which in turn removes ground from release trunk conductor 415 whereupon the switching relays 403 and 407 are deenergized. At armature 442 switching relay 407 completes a circuit for energizing the finder release magnet as follows: from ground by way of armature 442, armature 437, armature 426 and its working contact, vertical off-normal springs 414 and through the winding of release magnet 457 to battery. By the operation of the release magnet the finder switch wipers are restored to their normal position and the vertical off-normal springs are opened. The operation of the vertical off-normal springs 413

5 opens the upper locking circuit extending through the upper winding of transfer relay 404 but this relay does not at this time deenergize, because the same is now energized over its lower winding connected to the common hold conductor 449.

10 On subsequent calls subsequent finders in the chain are taken into use and when the last idle finder in the chain has switched through the busy common relay 461 deenergizes in a manner previously described. At armature 471 busy common relay 461 transfers the start circuit from the start conductor 260 of the A group to start conductor 261 of the B group and at armature 472 removes ground from conductor 115 for unlocking relay 560 in case the same at this time may be energized. At armature 470 busy common relay disconnects ground from the common hold conductor 449 with the result that the locking circuit through the lower windings of the transfer relays in all of the finders in the A group are opened and, therefore, those finders which have returned to their normal 20 positions and have opened their upper locking circuits through the transfer relays 404 permit such transfer relays to deenergize and again restore the circuit for the connecting relays, such as relay 405. The finders which 25 at this time have not been released maintain their transfer relays in energized position throughout the next cycle of operation of the chain of finders. At armature 426 transfer relay 404 and other similar transfer relays 30 complete the multiple ground connection from armatures, such as armature 442, to the common conductor 448 whereupon the busy common relay 461 is again energized to prepare the locking circuit through the lower windings of the transfer relays at armature 470; and at armature 471 prepares the circuit 35 extending to the start relay 464, so that subsequent calls in the A group will operate the start relay 464.

40 In case the upper set of wipers 230 to 232, inclusive, are operated into engagement with a calling line the switching relay 406 in the finder is energized in place of the switching relay 407 and in this case the lower set of 45 wipers are not connected up. The switching relay 406 accomplishing similar functions to that described for switching relay 407.

50 Referring now to the common relay group RDA in Fig. 4, and at a time when the start relay 464 has been energized responsive to a call, it will now be assumed that negative battery is not connected to common conductor 454 by way of armature 430 and release trunk conductor 415 because of some fault.

55 Under these conditions test relay 463 will not energize with the result that the slow-to-operate relay 465 is energized. At armature 487 relay 465 opens the circuit of start relay 464 with the result that the start relay deenergizes and removes the shunt battery from

around the upper winding of transfer relay 404, it being remembered that connecting relay 405 energized responsive to the energization of the start relay 464. Transfer relay 404 now energizes in series with connecting relay 405 with the result that the transfer relay is locked up and the call is transferred to the next finder in the chain. Relay 465 deenergizes responsive to start relay 464 opening its locking circuit at armature 459.

70 Another condition which may arise is that the finder may not switch through within a predetermined time due to some fault. In this case the test relay 463 will be maintained energized for a sufficient time interval to 75 close the vibrating springs 478 to cause the energization of the slow-to-operate relay 460. Relay 460, upon energizing, at armature 467 opens the circuit of the busy common relay 461 and at armature 468 closes a locking circuit for itself over conductor 114. The deenergization of the busy common relay 461 connects the A start conductor 260 to the B start conductor 261, so that the calls now 80 originating in the A group are handled by the B group equipment until such time as the fault is corrected or until the locking circuit of relay 460 is opened as a result of all the 85 finder-selector links in the B group becoming busy. This operation last described is 90 similar to the operation described for the A group apparatus shown in Fig. 1.

95 Since the apparatus shown in Fig. 5 is identical with the apparatus shown in Fig. 4 its operation is the same as described for 100 Fig. 4 and it is, therefore, thought the detailed description thereof may be omitted.

Having described the invention what is 105 considered new and is desire to have protected by Letters Patent will be set forth in the following claims.

What is claimed is:

1. In a telephone system, an automatic switch, a group of test contacts in the bank of said switch, a test wiper having access to said contacts, means whereby each of said test contacts at certain times have a calling potential, a busying potential, a metering potential, or no potential connected thereto, a switching relay in said switch, means for seizing said switch, automatic means responsive to said seizure for operating said wiper step-by-step over said contacts, a circuit including the winding of said relay and said wiper for operating said relay, means for operating said relay over said circuit only when the test wiper engages a contact with a calling potential and means controlled by the operation of said relay for stopping said automatic operation.

2. In a telephone system, an automatic switch, a group of test contacts in the bank of said switch, a test wiper in said switch having access to said contacts, a switching relay in said switch having a polarizing

- winding and an operating winding, means for seizing said switch, means responsive to said seizure for energizing the polarizing winding of said relay to prepare it for operation, automatic means responsive to said seizure for operating the test wiper of said switch step-by-step over said contacts, a circuit for operating said relay including said operating winding, said test wiper and one of said contacts in series, means for operating said relay over said circuit, and contacts operated by said relay for stopping the automatic step-by-step operation of said wiper on said one contact.
5. In a telephone system, an automatic switch, a group of test contacts in the bank of said switch, a test wiper in said switch having access to said contacts, a switching relay in said switch having a polarizing winding and an operating winding, means for seizing said switch, means responsive to said seizure for energizing the polarizing winding of said relay to prepare it for operation, automatic means responsive to said seizure for operating the test wiper of said switch step-by-step over said contacts, a circuit for operating said relay including said operating winding, said test wiper and one of said contacts in series, means for operating said relay over said circuit, contacts operated by said relay for stopping the automatic step-by-step operation of said wiper on said one contact, and said relay maintained in energized position solely over its polarizing winding.
6. In a telephone system, an automatic switch, a group of test contacts in the bank of said switch, means whereby each of said contacts have at certain times a zero potential, a potential of one value, or a potential of another value connected thereto, a test wiper in said switch having access to said contacts, a switching relay in said switch having an operating winding, means for connecting a potential of a further different value to one of said contacts, means for seizing said switch, automatic means for operating the test wiper of said switch step-by-step over said contacts, a circuit including the operating winding of said relay and said test wiper ineffective for operating said relay responsive to the wiper engaging test contacts having zero potential, a potential of said one value, or a potential of said other value but effective for operating said relay responsive to the test wiper engaging the contact having a potential of said further different value connected thereto, and means controlled by the operation of said relay for stopping the automatic step-by-step operation.
7. In a telephone system, a finder switch, a group of subscribers' lines terminating in the bank contacts of said switch, the test contact of an idle line normally having a potential of zero value, a test wiper in said switch for connecting one of a plurality of potentials of different value to the test contacts of busy lines, a switching relay in said switch having a polarizing winding and an operating winding, means responsive to a call on one of said lines for connecting a calling potential of a further different value to the test contacts of a calling line, means responsive to said call for seizing said switch and for energizing the polarizing winding of the switching relay, automatic means for operating the test wiper of said switch step-by-step over the test contacts of idle and busy lines, a circuit including the operating winding of said relay and said test wiper ineffective responsive to said test wiper engaging test contacts having zero potential and said plurality of potentials of different value thereon but effective for operating said relay responsive to said wiper engaging a calling potential, and means controlled by the operation of said relay for stopping the wiper of the switch on the contact of the calling line.
8. In a telephone system, a plurality of finder switches, a group of subscribers' lines terminating in the bank contacts of said switches, the test contact of an idle line normally having no potential thereon, a test wiper in each switch for connecting a busy potential and a metering potential to the test contacts of busy lines, a switching relay in each switch having a polarizing winding and an operating winding, means responsive to a call on one of said lines for connecting a calling potential to the test contact of the calling line, means responsive to said call for seizing an idle one of said switches and for energizing the polarizing winding of the switching relay associated therewith, automatic means for operating the test wiper of said switch step-by-step over the test contacts of idle and busy lines, a circuit including the operating winding of the switching relay and said test wiper ineffective for operating said switching relay responsive to the test wiper engaging test contacts having no potential, busy potential, or metering potential thereon but effective for operating said relay responsive to said wiper engaging a calling potential, and means controlled by the operation of said switching relay for stopping the wiper of the switch on the contact of a calling line.
9. In a telephone system, a finder switch, two sets of wipers in said switch, a pair of talking conductors in said switch normally disconnected from said wipers, a pair of switching relays in said switch, means for energizing only the first switching relay to connect the first set of wipers to said conductors, and means for energizing only the second switching relay or both the first and second switching relays to connect the second set of wipers to said conductors.

second relays to connect only the second set of wipers to said conductors.

8. In an automatic telephone system, a subscriber's line comprising a line relay having only a single winding and only two pairs of make springs and a cut-off relay having only a single winding, only two pairs of break springs, and only a single pair of make springs, means responsive to the initiation of a call on said line for energizing said line relay over a circuit including the two pairs of break springs of the cut-off relay, a first circuit completed through the first pair of make springs on the line relay and a second circuit completed through the winding of the cut-off relay and the other pair of springs of the line relay responsive to the energization of the line relay for marking said line calling, means responsive thereto for establishing a connection with said line and for completing an energizing circuit for said cut-off relay including the said second circuit, and a holding circuit including the winding of the cut-off relay and its pair of make contacts completed responsive to the energization of the cut-off relay for maintaining it in energized position.

9. In an automatic telephone system, a subscriber's line comprising only a single wound line relay having only two pairs of make springs and a single wound cut-off relay having only two pairs of break springs and only a single pair of make springs, a finder having access to said line, a primary test contact associated with said line, a secondary test contact associated with said line, means responsive to the initiation of a call on said line for energizing said line relay over a circuit including the two pairs of break springs of the cut-off relay, a circuit completed through the first pair of make springs of the line relay and another circuit completed through the winding of the cut-off relay and the other pair of make springs of the line relay responsive to the energization of the line relay for marking said contacts as calling, wipers on said finder having access to said contacts, means in the finder controlled through said wipers to select said marked contacts and to establish a connection to said line, means responsive to the establishment of said connection for energizing the cut-off relay over a circuit including a wiper of said finder, the marked secondary contact, the said other pair of make springs of the line relay, and the winding of the cut-off relay, and a holding circuit for maintaining the cut-off relay in energized position including its winding, its make springs, and the secondary test contact.

10. In a telephone system, a group of finder switches having vertical and rotary movements to find a calling line, a vertical magnet in each finder for operating the finder in its vertical movement, a rotary magnet in each finder for operating the finder in its rotary

movement, means for closing a circuit to the vertical magnet of one of said finders to energize it, a pulse-ending relay common to said finders, means controlled by the vertical magnet in its energized position for energizing the pulse-ending relay to open the circuit to the vertical magnet, a changeover relay common to said finders, means for energizing the changeover relay in series with the pulse-ending relay, means controlled by the energization of the changeover relay for deenergizing the pulse-ending relay and for changing the circuit from the vertical magnet to the rotary magnet of the operated finder to energize the rotary magnet, means controlled by the rotary magnet in its energized position for energizing the pulse-ending relay to open the circuit to the rotary magnet, two test relays in the operated finder, means for energizing either one of said test relays, and means controlled by the energized test relay for opening the circuit of the rotary magnet to stop the finder on the calling line.

11. In a telephone system, a group of finders having vertical and rotary movements to find a calling line, a vertical magnet in each finder for controlling the vertical movement of the finder, a rotary magnet in each finder for controlling the rotary movement of the finder, a common stepping circuit for operating said vertical and rotary magnets, means common to said finders for first closing said circuit to the vertical magnet of one of said finders and then to rotary magnet thereof, and a pulse-ending relay common to all of said magnets energized responsive to each energization of the vertical and rotary magnets for opening said circuit to the finder magnets to operate the finder step-by-step in its vertical and rotary movements to the calling line.

12. In a telephone system, a group of finders having vertical and rotary movements to find a calling line, a vertical magnet in each finder for operating the finder in its vertical movement, a rotary magnet in each finder for operating the finder in its rotary movement, a common stepping circuit for operating the vertical and rotary magnets of said finders, a common pulse-ending relay for controlling said circuit, means common to said finders for closing said circuit to the vertical magnet of one of said finders to energize it, means controlled by the vertical magnet in its energized position for energizing the common pulse-ending relay to open said circuit to the vertical magnet, means for changing said circuit from the vertical magnet to the rotary magnet of the operated finder to energize it, means controlled by the rotary magnet in its energized position for energizing the pulse-ending relay to open said circuit to the rotary magnet, and means for stopping the operated finder on the calling line.

13. In a telephone system, a group of finders each having a vertical movement and a rotary movement to find a calling line; an auxiliary start relay, a pulse-ending relay, and a changeover relay common to said finders in the group; means for operating said start relay to initiate the vertical movement of one of said finders, means for operating said pulse-ending relay to control the step-by-step vertical movement of said finder, means for operating said changeover relay to stop the vertical movement and start the rotary movement, means for operating the pulse-ending relay to control the step-by-step rotary movement of said finder, and means operative in case any one of said relays fail to operate properly in response to a call for operating an alarm. 70
14. In a telephone system, a group of finders each having a vertical movement and a rotary movement to find a calling line; an auxiliary start relay, a pulse-ending relay, and a changeover relay common to said finders in the group; means for operating said start relay to initiate the vertical movement of one of said finders, means for operating said pulse-ending relay to control the step-by-step vertical movement of said finder, means for operating said changeover relay to stop the vertical movement and start the rotary movement, means for operating the pulse-ending relay to control the step-by-step rotary movement of said finder, means operative in case any one of said relays fail to operate properly in response to a call for operating an alarm, and means responsive thereto for associating said common relays with another one of said finders. 75
15. In a telephone system, a group of finders each having a vertical movement and a rotary movement to find a calling line; an auxiliary start relay, a pulse-ending relay, and a changeover relay common to said finders in the group; means for operating said start relay to initiate the vertical movement of one of said finders, means for operating said pulse-ending relay to control the step-by-step vertical movement of said finder, means for operating said changeover relay to stop the vertical movement and start the rotary movement, means for operating the pulse-ending relay to control the step-by-step rotary movement of said finder, means operative in case any one of said relays fail to operate properly in response to a call for operating an alarm, means responsive thereto for associating said common relays with another one of said finders, and means operative in case any one of said relays fail to operate a second time on this call for operating an emergency alarm and for rendering said finders inaccessible for finding calling lines. 80
16. In a telephone system, a group of finders each having a vertical magnet and a ro- 85
- tary magnet for operating the finders in their vertical and rotary movements to find a calling line, a relay allotter comprising a group of relays common to said finders, common control conductors extending from said relay allotter to each of said finders, a connecting relay in each of said finders, means in said allotter responsive to a call for energizing the connecting relay of an idle one of said finders to operatively connect said common conductors to said finder, means in said allotter responsive thereto for controlling the vertical and rotary magnets of said finder over said conductors, a transfer relay in each finder, and means in said allotter responsive to the said finder finding the calling line for operating the transfer relay of said finder to disconnect the said connecting relay of said finder from said allotter and for connecting the connecting relay of another finder to said relay allotter. 90
17. In a telephone system, a group of finders each having a vertical magnet and a rotary magnet for operating the finders in their vertical and rotary movements to find a calling line, a relay allotter comprising a group of relays common to said finders, common control conductors extending from said relay allotter to each of said finders, a connecting relay in each of said finders, means in said allotter responsive to a call for energizing the connecting relay of an idle one of said finders to operatively connect said common conductors to said finder, means in said allotter responsive thereto for controlling the vertical and rotary magnets of said finder over said conductors, a transfer relay in each finder, means in said allotter responsive to the said finder finding the calling line for operating the transfer relay of said finder to disconnect the said connecting relay of said finder from said allotter and for connecting the connecting relay of another finder to said relay allotter, means for locking said transfer relay in operated position, means for releasing said finder without deenergizing said transfer relay to maintain said finder unselectable for use, and means in said allotter for deenergizing said transfer relay to again render said finder selectable for use. 95
18. In a telephone system, automatic switches, a group of subscribers' lines terminating in the bank contacts of said switches, the test contacts of idle subscribers' lines normally having a potential of zero value, a test wiper in each of said switches for connecting a plurality of potentials of different value to the said test contacts of busy subscribers' lines, subscriber controlled means for connecting a potential of a further different value to one of said test contacts, means for seizing one of said switches and for automatically operating the test wiper of the switch over the test contacts of idle and busy subscribers' 100

- lines, a switching relay in said switch, a circuit including a winding of said relay and the test wiper in said switch ineffective for operating said relay responsive to said test wiper engaging test contacts having zero potential and said plurality of potentials of different value thereon but effective for operating said relay responsive to said test wiper engaging a test contact having said potential of a further different value.
- 5 19. In an automatic telephone system, a group of subscribers' lines, a group of finders having access to said lines, means including an allotter for preselecting an idle one of said finders, a pulse ending relay in said allotter of a further different value, and means controlled by the operation of said relay for stopping the automatic operation of the wiper of said switch on the contact having said potential of a further different value.
- 10 20. In an automatic telephone system, a group of subscribers' lines, a group of finders having access to said lines, means including an allotter for preselecting an idle one of said finders, a pulse ending relay in said allotter common to the finders in said group, a start relay in said allotter, means responsive to the initiation of a call on one of said lines for energizing said start relay, a test relay in said allotter energized responsive to the energization of said start relay only in case the preselected idle finder is in normal position, means in said finder operated responsive to the operation of said test relay for energizing said common pulse ending relay, and means controlled by said pulse ending relay and said last means for operating the finder step-by-step in search of the calling line.
- 15 21. In a telephone system, a group of finder switches having vertical and rotary hunting movements to find a calling line in a group of lines, a pulse ending relay common to said finders, means responsive to a call and including said relay for operating one of said finders step-by-step in its vertical movement in search of the group of lines containing the calling line, a changeover relay common to said finders responsive to the finder finding the calling group for stopping the finder opposite such group and for closing a stepping circuit, means including said circuit and said pulse ending relay for operating said finder step-by-step in search of the contacts associated with the calling line, and a switching relay in said finder for opening said stepping circuit to stop the finder on the calling line.
- 20 22. In a telephone system, a group of subscribers' lines, a group of finders having access to said lines, an allotter having access to said finders, means in said allotter for making a first test to preselect an idle one of said finders, means in said allotter responsive to a call on one of said lines for then making a second test to seize the preselected finder in case said finder is in normal condition, means for operating said first means to preselect another finder in case said first preselected finder does not test normal, and relays in said allotter common to said finders for thereafter
